FORREST ANDREWS, OF KNOXVILLE, TENNESSEE.

DROP-BOTTOM DUMP CAR.

Application filed February 15, 1926. Serial No. 66,458.

This invention relates to drop-bottom cars for use in transporting and dumping loose materials such as coal, earth, ores and the like, and has for its object to provide a car 5 of this type which shall be strong, durable, simple in construction, and of efficient operation.

In cars of this type it is desirable to provide a drop-bottom which is automatically released at the dumping station and automatically actuated to close as the car leaves such dumping station. It is usual in such cars to provide a plurality of successively operating bottom closure members or doors, 15 and to provide suitable locking means to assure that the doors shall remain closed at all times except when passing the dumping station. It has heretofore been proposed to employ a plurality of doors hinged either on the car axles or on stationary 20 pivots secured to the car body and having the rear edge or lip at each door (except the rear one) adapted to rest on some portion of the next succeeding door when in closed 25 position, while the rear edge of the rear door is supported by a latch, which latch when tripped first frees the rear door, which in dumping frees the next door to the front, and this latter door in turn frees the door 30 in front of it. In such structures the doors are released successively and each door necessarily approaches its fully open position before the next door in the forward direction is released. The disadvantages of this 35 operation are obvious. Where the distance to be travelled in crossing the dumping station is small, the speed of the car must be slow because the operation of the doors is successive and the car is dumped, as it were, 40 back end first. Moreover, when the rear door is released from the retaining latch which holds it in closed position, said rear door has to approach full dumping position before the next succeeding door is released, 45 and in the act of reaching such dumping position the forward edge of the door resting thereon has to be lifted, through the dumping action of the rear door, before said next succeeding door can be released.

According to the present invention, the car is provided with a plurality of drop-bottom doors, one of which is mounted to turn on a horizontally swinging axis, combined with means actuated on the closure of 55 the doors and imparting swinging movement to said axis, in which said swinging

movement said axis moves a supporting element into engagement with the next adjacent door to hold the same in closed position. Conversely, when the door mounted on the 60 swinging axis is released and the axis swings in the reverse or rearward direction, said axis in its movement withdraws the supporting means from supporting engagement with the next forward door, thereby freeing said 65 door. There may be, and preferably is, a plurality of doors mounted upon swinging axes, each of which in turn operates as indicated above. The means actuated by the swinging axes to be thrown into supporting 70 engagement with the next forward door may be embodied in a variety of forms without departing from the present invention. Preferably, and as here shown, such means consists of a projection on the door itself 75 extending forward beyond the swinging axis into a position to be engaged by a projecting lip on the next succeeding door. The rear edge of the rear door is engaged by a swinging latch, which in the act of closing imparts 80 a forward thrust to the door, thereby imparting a forward swing to the axis upon which the door is mounted, and this axis in its rearward movement imparts a rearward swing to the next succeeding door, and so 85 on through the series. Conversely, when the latch is tripped, the weight of the material on the doors imparts a rearward swing to the doors, thereby automatically and almost simultaneously tripping all of the doors. 90

The tripping of the doors may occur, if desired, at the time when the car is immediately over the dump. Preferably, however, the automatic tripping of the retaining latch is timed so as to occur just before 95 the car reaches the dump, and in order to prevent the load from being discharged before the dump is reached, means, such for example as a rail extending between the two track rails and parallel therewith, is provided upon which the doors rest, which rail extends to, and on the edge of the dump, extends downwardly. The result of this is that all of the doors are free and ready for the dumping action and, as the forward door 100 reaches the drop in the retaining rail, it drops and delivers its load and the remaining doors deliver their load in succession, the rear door being the last to discharge.

On the far side of the dump, a central 110 cam rail is provided extending between and parallel to the track rails and into posi-

tion somewhat above said rails. As the forward door reaches this cam rail, it is raised into closed position, and each succeeding door is likewise so raised, and as the rear door is raised it engages the latch which, in its closing movement, swings the entire series of doors except the forward door forward, and in so doing swings the door axes, previously referred to, forward, carrying with them the means for engaging and supporting the rear edges of the doors in the series, as above described.

The inventive idea is capable of receiving a variety of mechanical expressions, one of which is illustrated in the accompanying drawings, which drawings are, however, for the purposes of illustration only and are not to be taken as defining the limits of the invention, reference being had to the appended claims for this purpose.

In said drawings:—

Fig. 1 is a diagrammatic illustration showing three cars, one approaching the dumping station, one over the dumping station in the act of dumping, and the third in the position which the parts assume as the car leaves the dumping station;

Fig. 2 is a rear elevation of a car embodying the invention;

Fig. 3 is a reduced plan view of Fig. 2;

Fig. 4 is a longitudinal sectional elevation showing the position of the doors on approaching the dumping station, with the retaining latch released;

Fig. 5 is a like view showing the doors in fully open position over the dumping station; and

Fig. 6 is a similar view showing the doors in closed and locked position on leaving the dumping station.

Referring to the drawings, in which like reference numerals indicate like parts throughout the several views, 1 is a car body of any suitable construction supported on axles 2, 2, which in turn are carried by wheels 3, 3, the car being preferably provided with forward and rearward bumpers 4 and 5. The bottom closure of the car is preferably composed of a plurality of hinged members here shown in the form of three doors 6, 7 and 8, preferably of concave form and having upwardly extending sides. The forward door 6 is mounted to turn on any suitable axis 9, here shown as supported in the car body, in any suitable manner. The doors 7 and 8, however, are mounted on axes 10 and 11, which axes are in turn carried by links 12 and 13, respectively, there being two of such links for each axis, one at either end. These links are mounted to swing on the axles of the car. The result of this construction is that each of the doors 6 and 7 can turn on its axis, which axis can swing or oscillate backward or forward on the axles of the car, the for-

ward swinging movement of the links being limited by suitable stops here shown in the form of pins 14' and 14'', projecting inward from the sides of the car body 1 and in like manner the rearward swinging movement of the links may, if desired, be limited by similar stops 14, 14.

Mounted to turn on a horizontal pivot 15 supported at the rear of the car, as on the bumper 5, is a bell-crank shaped latch 16 provided in its lower end with a notch 17. A bell-crank lever 18 (Fig. 2) is mounted to turn upon a pivot 19 with one arm 20 extending out horizontally beyond the side of the car, while its other arm 21 extends downward and is provided with a shoulder 22. The long arm 20, being much heavier than the arm 21, tends to rotate the lever about fulcrum pin 19 and throw the shoulder 22 under the latch 16 when the same is in raised position, as will be readily understood from an inspection of Fig. 2, said latch 16 in moving to its upper position engaging the cam face 23 on the lower end portion of the arm 21 to tilt the same to the right in Fig. 2 in order to permit the latch 16 to come to its upper position.

Referring now to Figs. 1, 4, 5 and 6, it will be understood that the car is moving from left to right on the rails 24, 24, and as it approaches the dumping station, but before it reaches the same, a cam rail 25 mounted at the side of the track (see Fig. 2) operates to lift the arm 20 of the bell-crank lever, thereby withdrawing the shoulder 22 from under the latch 16, which latch then falls into the position shown in Fig. 4, and the left of Fig. 1, permitting the door 8 to fall therewith until the concave bottom of the door rests upon the midrail 26. In falling, the door 8, with its axis 11, swings rearward, withdrawing the projection which extends to the forward side of the link from under the nose 7' of the door 7, which in turn falls upon the rail 26, withdrawing the projection at the forward side of the axis 10 from under the lip 6' of the door 6. The doors 6, 7 and 8 are all thus resting upon and supported by the rail 26, as shown in Fig. 4. As the car reaches the dumping station, the door 6, owing to the downward incline of the rail 26, is permitted to fall into fully open position. Thereafter, the doors 7 and 8 in succession fall into open position and discharge the load. This is the position shown in the center of Fig. 1 and in Fig. 5. As the car advances from left to right, the door 6 first comes in contact with the cam rail 27, which rail it will be observed at its highest point is raised an appreciable distance above the rails 24. This cam rail 27 acts to raise first the door 6 and then the door 7 into fully closed position and then to raise the door 8 into the same position. As the door 8 is moved up-

ward, its forward lip engages the notch 17 closure of the doors and imparting swinging movement to said axis, and means carried by said swinging axis into supporting engagement with the next adjacent door when said doors are in closed position. 70

5 this movement being permitted by the swinging action of the links 13. When the door 8 and the latch 16 have reached their highest position, the shoulder 22 on the trip lever 18 passes thereunder and supports the latch 10 as shown in Fig. 2. The forward swinging movement of the door 8 causes the rear projection of said door to engage the door 7, such projection passing under the lip 7' of said door, and a like swinging movement is 15 imparted to the door 7 and its axis 10, bringing the projection on the door 7 under the lip 6' of the door 6, all as clearly shown in Fig. 6. The forward swinging movement of the links 12 and 13 being preferably limited by stops 14', 14".

It will be observed that, in the act of freeing the doors and dumping the car, the doors are successively freed ready for the dumping action without having to overcome 25 resistance due to the weight of the load carried on the doors, and hence that the swinging action will be freely and readily accomplished.

It will be seen from the foregoing that 30 the present invention provides a dumping car wherein the load is dumped by the forward doors first and the succeeding door of the series in succession, and that as a result of this construction, the car may be moved more rapidly over the dumping station while effecting the dumping action; or, that the width of the dumping station may be materially decreased without danger of any of the load being dumped elsewhere than at 40 such station. It will also be appreciated that the construction is one of great strength, and simplicity, and therefore not liable to get out of order, and that, in the operation of tripping the doors, the resistance due to the 45 weight of the load does not have to be overcome and that therefore the tripping action can be effected with greater facility and without placing undue strain upon the parts.

While the invention has been described in 50 its preferred form, it will of course be appreciated by those skilled in the art that various modifications of the specific construction herein shown and described may be made without departing from the spirit 55 of the invention. The scope of the invention, therefore, is not to be taken as limited by the specific construction shown herein to illustrate the invention, but reference is to be had to the appended claims for this purpose. 60

What is claimed is:—

1. In a drop-bottom dump car, the combination of a plurality of drop-bottom doors one of which is mounted to turn on a horizontal swinging axis, means actuated on the

2. In a drop-bottom dump car, the combination of a drop-bottom door hinged to the car, a second drop-bottom door mounted to turn on a horizontal swinging axis, means actuated on the closure of said second door 75 and imparting swinging movement to said axis, and means carried by said axis into supporting engagement with said first-named door.

3. In a drop-bottom dump car, the combination of a drop-bottom door hinged to the car, a plurality of drop-bottom doors mounted to turn on horizontal swinging axes, means actuated on the closure of the doors and imparting swinging movement to said 85 axes, and means carried by each of said axes into supporting engagement with the next adjacent door.

4. In a drop-bottom dump car, the combination of a drop-bottom door hinged to the forward end of the car, a plurality of drop-bottom doors arranged in series to the rear of said first-named door and each mounted to turn on a horizontal swinging axis, means actuated on the closure of the rear door in 90 said series and imparting swinging movement to said swinging axes, and means carried by each of said axes into supporting engagement with the next adjacent door in 95 front thereof. 100

5. In a drop-bottom dump car, the combination of the car body and axles supporting the same, with a bottom door hinged to the forward part of the car, a second door mounted to turn on a swinging axis to the 105 rear of said first-named door, and means on said second door supporting said first door when the same are in closed locked position.

6. In a drop-bottom dump car, the combination of a series of bottom closure doors arranged one in front of the other, an axis on which the front door turns at its forward end, a swinging axis for each of the other doors of the series, means imparting a swinging movement to said axes on closing the 115 doors, and means actuated by said swinging movement into supporting engagement with each door immediately in the rear of each swinging axis. 120

7. In a drop-bottom dump car, the combination of a car body and axles supporting the same, with a pair of links swinging from one of said axles, a door mounted to turn on an axis supported by said links, a second door hinged in front of said first-named door with its free edge adjacent said link supported axis, means imparting swinging movement to said links and the axis carried thereby on the closure of the doors, and means actuated by said swinging movement 130

into supporting engagement with said second door.

8. In a drop-bottom dump car, the combination of a car body, and axles supporting the same, a door carried on each axle by swinging links, whereby said doors may swing on said axles longitudinally of the car, a projection on each door to the front of said links, and an upwardly and forwardly moving latch engaged by the rearmost door in its closing movement, whereby said doors are swung forward and the said projections thereon are moved into supporting engagement with the rear edge of the door next in front.

9. In a drop-bottom dump car, the combi-

nation of a car body, and axles supporting the same, with a hinge rod, a door mounted to turn on said rod, a swinging support for said rod whereby the same is free to swing longitudinally of the car, a door mounted to turn on said rod, a vertically and forwardly swinging latch engaged by the rear portion of said door during its closing movement, whereby a forward swinging movement is imparted to said door, and a second door engaged and held in closed position by the forward portions of said swinging door.

In testimony whereof I have signed this specification.

FORREST ANDREWS.
